UNITED STATES PATENT OFFICE

HERBERT A. CLARK, OF ROCHESTER, NEW YORK, ASSIGNOR TO TAYLOR INSTRUMENT COMPANIES, OF ROCHESTER, NEW YORK, A CORPORATION OF NEW YORK

PRESSURE GAUGE

Application filed March 29, 1928. Serial No. 265,745.

This invention relates to pressure gauges of the type in which a column of liquid, usually mercury in a tube closed at one end is balanced against the pressure to be measured.

Instruments of this type have one considerable disadvantage: During shipment, when the column may be in a horizontal position, air may find its way to the end or top of the column and thereby destroy the value of the instrument. It is a common practice to have the outlet of the mercury tube so disposed in the well that the outlet is immersed in the liquid irrespective of the position of the instrument. However, heavy shocks and vibrations often cause a displacement of the liquid so that air contained in the well can enter into the tube and creep to the closed end of the tube.

It is the object of the present invention to practically eliminate this danger and to provide a gauge construction in which a positive seal may be provided against entrance of air into the tube containing the column of liquid.

In order to fully explain the invention and the principal points of novelty involved, reference is made to the accompanying drawings, which represents a section through a device embodying the invention, in the particular instance an absolute pressure gauge.

In the drawings, 1 represents a glass tube normally containing mercury or other suitable liquid. The tube 1 is connected at its bottom with a well 2 by means of a crook portion 1a. The well 2 is preferably an iron casing since iron is chemically immune against mercury. The connection between the crook portion of the tube and the well 2 is made by means of a suitable union 3. The well has an outlet 4 through which it may be connected with the atmosphere or any other gas of which the pressure is to be measured.

The mechanism thus far described represents a typical construction in general use.

The invention consists in mechanism operable at will to positively seal the tube against leakage of air or other gas into the column of liquid.

To this end I have provided as part of the

well 2 and depressed from the bottom thereof, a depression or auxiliary chamber 5 for cooperation with a piston 6 disposed for movement into and out of the chamber 5. The chamber 5 and the piston 6 are so accurately machined and fitted that the interspace between the two does not permit mercury to flow through it. Thus, when the piston is lowered into position in the chamber against the mercury contained therein, air can not come into contact with the mercury, but finds a solid-filled mercury column positively barring flow into the column irrespective of the position of the tube.

The piston 6 is preferably supported from the top of the well and made adjustable in vertical direction by means of a screw-threaded shank 7 co-operating with a correspondingly screw-threaded bore 8 or any other equivalent means. The upper end of the shank 7 may be provided with a screw driver slot, as indicated, or any other means for effecting turning movement of the shank.

In order to provide for expansion and contraction of the mercury confined in the column by means of the piston 6, I provide the latter with means for resiliently pressing upon the mercury. While there are various means available for this purpose, I make the piston of two component parts movable relatively to each other in axial direction and provide spring means 9 tending to move the parts away from each other. I preferably provide the part 6a with a bore 6c and the part 6b with a tenon 6d loosely fitting the bore 6c, the compression spring 9 being mounted on the tenon 6b and bearing upon the opposing surfaces of the parts 6a and 6b. To prevent separation of the parts 6a and 6b, the tenon 6d may be provided with a groove 6e and the part 6a with a set screw 6f for engagement with the groove 6e.

The outlet 4 and the bore 8 have closures 4a and 8a respectively for tightly sealing the openings against loss of mercury during shipment.

The operation is as follows:

The tube 1 is normally completely filled with mercury and the surface to be acted upon by the air or gas, i. e. the level of the

mercury is in the well. For shipment of the instrument, the closure 8a is removed and by means of a screw-driver or wrench the shank 7, which, of course, has a recess for engagement by the screw-driver or the wrench, is turned to lower the piston into the chamber

5. The piston moves freely until the piston enters the chamber 5 and forms a seal. Since the mercury is incompressible, the piston can move no farther and continued movement of the shank 7 and part 6b serves to compress spring 9. While the temperature remains the same, the piston will remain the same. With increase of temperature, part of the 10 confined mercury is forced out against the resistance of spring 9. With decrease of temperature, the piston, under the action of spring 9, follows the receding mercury.

However, I prefer to carry out the operation in slightly different form. I first evacuate the well until the top of the column in tube 1 is depressed to a point a small distance from the end of the tube and in this condition I lower the piston into the chamber 5. Now, 20 by continuing the downward movement of the shank 7, the piston can advance in the chamber until the column again completely fills the tube and then the movement of the shank is continued until the spring 9 has been 25 compressed to the desired degree.

The dimensions of the chamber 5 and the spring 9 are such that the head surface of the piston remains within the chamber for all 30 temperatures within the range chosen. The degree of evacuation preparatory to the operation of the piston, is then so chosen that the head surface of the piston initially assumes a position within the chamber 5 approximately 35 corresponding to the surrounding temperature. Thus, assuming that the temperature range contemplated is -30° to 200° and the temperature at the point of shipment is 40°, the difference between 40° and -30° is 70°, while the difference between 40° and 200° is 40 45 160°. To take care of the changes of temperature within the range indicated, the evacuation should be so conducted that the head surface of the piston under the desired pressure is about at the dotted line P.

50 In order to avoid sudden fluctuations and hammer action in the tube 1, I have the connecting conduit in the crook portion 1a in the form of a capillary tube 1b, as indicated.

55 In the foregoing, I have described what I consider the preferred embodiment of my invention. However, it is understood that the invention may be carried out in various other ways. The invention essentially comprises a positive seal and means for permitting variations in the column of the liquid within the space confined by the seal. The relation of the sealing means and the means permitting the changes of volume may assume many different forms.

While I have specifically described what is known as an absolute pressure gauge, the invention may find expression in various other forms of gauges. The well may be made of glass or other suitable material.

70 I claim:

1. In apparatus of the character described, the combination with a tube closed at the top, a well, a U-shaped connection between the well and the bottom of the tube, a liquid in the tube and partly filling the well, the well having an outlet above the level of the liquid, of means for interrupting communication between the tube and the well, resilient means 75 operative when the said interrupting means is effective, to permit expansion of the liquid in the tube.

2. In apparatus of the character described, the combination with a tube closed at the top, a well, a U-shaped connection between the well and the bottom of the tube, a liquid in the tube and partly filling the well, the well having an outlet above the level of the liquid, of means for interrupting communication between the tube and the well, and resilient 80 means operatively connected with the interrupting means for permitting, when the latter is effective, expansion of the liquid in the tube.

25 3. In apparatus of the character described, the combination with a tube, a well having a relatively thick bottom wall and a cylindrical depression in the bottom wall, the tube being closed at the top and having at the bottom a U-shaped connection to the bottom of 100 said depression, and a liquid filling the tube and partly filling the well, the latter having an outlet above the level of the liquid, of a piston accurately fitting the said depression and disposed above the latter, means for moving the piston into and out of the said depression, and means for permitting expansive movement of the liquid in the tube when the piston is disposed in the depression.

4. In apparatus of the character described, the combination with a tube, a well having a relatively thick bottom wall and a cylindrical depression in the bottom wall, the tube being closed at the top and having at the bottom a U-shaped connection to the bottom of 105 said depression, and a liquid filling the tube and partly filling the well, the latter having an outlet above the level of the liquid, of a piston accurately fitting the said depression and disposed above the latter, means for moving the piston into and out of the said depression and means for permitting expansive movement of the liquid in the tube when the piston is disposed in the depression, comprising resilient 110 means between the piston and the means for moving it.

5. In apparatus of the character described, the combination with a tube closed at the top, a well, a U-shaped connection between the well and the bottom of the tube, a liquid in 115 120 125 130

the tube and in the well, the well having an outlet above the level of the liquid, of means between the bottom of the well and the level of the liquid in the well operable at will to inhibit the flow of liquid from the tube into the well and means associated with the said inhibiting means for resiliently yielding to the pressure of the liquid in the tube.

10 In testimony whereof I affix my signature.
HERBERT A. CLARK.
